UNITED STATES PATENT OFFICE.

HARRY AUPERL, OF MINNEAPOLIS, MINNESOTA.

AMUSEMENT SLIDE.

Application filed August 4, 1924. Serial No. 729,896.

To all whom it may concern:

Be it known that I, HARRY AUPERL, a citizen of the United States, residing at Minneapolis, in the county of Hennepin and 5 State of Minnesota, have invented certain new and useful Improvements in Amusement Slides; and I do hereby declare the following to be a full, clear, and exact description of the invention, such as will 10 enable others skilled in the art to which it appertains to make and use the same.

This invention relates to an amusement device, particularly, to such a device adapted to be used adjacent a body of water. 15 Such an amusement device will be used at a summer or pleasure resort where a body of water is available.

It is an object of this invention to provide an amusement device comprising an 20 elevated support having a track running up and over said support and downward therefrom into a body of water, together with an aqueduct leading from the body of water to and into alignment with the end of the 25 track disposed away from said body of water, a boat adapted to run on said track being provided, together with means for elevating the boat on the track to the top of said support and releasing the same, and 30 means for creating a current in said aqueduct.

It is a further object of the invention to provide a novel structure of supporting means and track support, a novel elevating 35 means for the boat and other novel features which will be fully set forth in the following description.

The invention is illustrated in the accompanying drawings in which like reference 40 characters refer to the same parts throughout the different views, and in which,

Fig. 1 is a general perspective view of the device;

Fig. 2 is a view partly in central vertical 45 section through the top of the support, and partly in side elevation;

Fig. 3 is a vertical section taken on the line 3—3 of Fig. 2, as indicated by the arrows;

Fig. 4 is a partial view in side elevation of the lower part of one end of the track and boat elevating means, a portion of said view being shown in vertical section;

Fig. 5 is a view in transverse vertical section of the aqueduct used showing the boat therein;

Fig. 6 is a fragmentary view in side elevation showing a modified form of stop used, Figs. 2 to 6 being shown on an enlarged scale; and

Fig. 7 is a vertical section taken substantially on the line 7—7 of Fig. 1 as indicated by the arrows.

The device of this invention is adapted to be used adjacent a body of water. Referring to the drawings, particularly Fig. 1, such a body of water is designated as B and adjacent the same are disposed two elevated supporting members 8. While any form of supporting members may be used, in the embodiment of the invention illustrated, the members 8 are shown as in the form of poles, such as the ordinary telegraph poles. Disposed at the top of each of the members 8 is secured an arcuate rigid member 9 having its convex side directed upwardly, said members having horizontal cross pieces disposed as chords thereof which are bolted to the supports 8. The members 9 will preferably have grooves at their top and end 80 portions and track cables 10 and 11 are secured at the respective ends of said arcuate members. The cables 10 and 11 may be secured by welding or any suitable clamping means. The cables 10 form a track extending downwardly from the supports 8 and members 9 into the body of water B and these cables are secured to anchoring stakes 12 disposed in deep water in the bottom of the body of water B. The cables 10, preferably, are tied together with U-shaped brace members 13 extending beneath the same and tension cables 14 are secured to the cables 10 or the members 13 and extend downwardly to anchoring stakes 15 disposed on the shore, these anchoring cables preferably being provided with turn buckles. By means of the cables 14, the desired tension 90

can be given to the cables 10 and the lower portion of the cables 10 brought more nearly into line with the surface of the water. The cables 11 extend downward away from the body of water B and have their lower ends anchored to suitable bolts or stakes disposed in the bottom of a trough or aqueduct 16. 100 The aqueduct 16 extends inward from the body of water B and is curved to align with the track formed by cables 11 and extends therefrom back into the body of water B passing between the supports 8 and beneath the cables 11. A platform is secured to and 105 between the supports 8 on which is support.

ed a motor 17, and a transverse shaft 18 is supported in suitable bearings secured to the supports 8 a short distance below the platform carrying motor 17. A shaft 18 carries a pulley 19 driven by a suitable belt 20 from a pulley on the motor shaft of motor 17. The shaft 18 also has a sprocket 21 secured thereto over which runs an endless chain 22 also passing over and driving 5 a sprocket 23 secured to a shaft 24 extending horizontally and supported in suitable bearings on the cross members supporting the members 9. The shaft 24 also carries a sprocket 25 disposed centrally between the supports 8 and an endless chain 26 runs 10 over and is driven by said sprocket. The chain 26 has spaced links connected by cross pieces 27 of appreciable length and said chain runs over supporting pulleys or sheaves 28 and a lower sprocket 29. The sprocket 29 and the sheaves supporting the top run of chain 26 are so disposed that the top run of said chain travels substantially parallel to the cables 11. A plurality of 15 vertical supporting posts 30 arranged in pairs support a pair of inclined spaced frame members 31 which are disposed a short distance at each side and below the chain 26. Plates 32 of considerably smaller 20 than the members 31 are secured to the inner side of said members adjacent the top edges thereof and form guiding means in the top run of chain 26. The frame members 31 have pivoted to their outer sides 25 by the pivots 33, swinging arms 34, the upper ends of which are beveled to extend in a line substantially normal to the upper run of chain 26. The arms 34 are adapted, when in substantially vertical position, to 30 engage stop blocks or members 35 also secured to the outer sides of the frame members 31.

The aqueduct 16, which, as stated, is in the shape of a trough, may be made of wooden 45 boards or concrete, as shown, (see Figs. 4 and 5). A boat 36 is provided and preferably will be of a size capable of seating two persons. The said boat has secured thereto at its sides, inverted U-shaped 50 brackets 37 in which are mounted sheave pulleys 37^a. The sheave pulleys are of special design and have very deep grooves therein and said pulleys form supporting means or trucks adapted to run on the cables 55 10 and 11. The boat 36 also has secured at the bottom thereof a rack 38 having rearwardly directed spaced and substantially pointed teeth forming a saw-toothed rack. Said boat is also provided with a steering 60 rudder 39 adapted to be operated from the steering wheel 39^a disposed in convenient position for an operator sitting on the front seat of the boat. While said steering means may be of any standard and suitable 65 type, in the embodiment of the invention

illustrated, the same is shown as disposed at the upwardly inclined front portion or prow of the boat. The boat 36 is adapted to move in the aqueduct 16 and to be carried up on the cables 11 by the chain 26, as will 70 be later described.

In order to maintain a current in the aqueduct 16 so that a boat 36 will travel therein without being propelled, a paddle wheel 40 is provided having an axle mounted in bearings carried by a pair of the posts 30, the lower portion of said paddle wheel being disposed in the aqueduct 16. The wheel 40 is thus disposed beneath the track formed by the tables 11 and beneath the members 31. 80 The axle of the wheel 40 carries a sprocket 41 driven by an endless chain 42 passing over and driven from a sprocket 43. The sprocket 43 is carried on a shaft 44, which shaft is mounted in suitable bearings carried on the supporting members 8 and is driven by a gear 45 secured thereto, which, in turn, meshes with and is driven by a smaller gear 46 secured to the shaft 18. Parallel walls 47 are disposed at each side of the aqueduct 90 16 adjacent the wheel 40 to prevent any water being splashed out of said aqueduct.

In Fig. 6, a modified form of stop for the swinging arms 34 is shown. Instead of having the blocks 35, the arms 34 have chains 48 secured to the lower ends, which chains are secured at their other ends to the sides of the members 31. It will be seen that the upper portion of the arms 34 can swing forwardly or to the left, as shown in Fig. 6, but 100 cannot swing backwardly beyond their vertical position.

In operation, the motor 17 will be driven and the chain 26 will be traversed in the direction indicated by the arrows in Figs. 2 and 4. The water wheel 40 will also be driven in the direction indicated by the arrows in Fig. 1. A current will thus be created and maintained in the aqueduct 16, as indicated by the arrows in Fig. 1. The 110 persons using the device will step into the boat 36 at some point along the side of the aqueduct 16. The boat will be carried by the current around through said aqueduct and will come into alignment with the track formed by cables 11. As the boat moves between the cables 11, the pins 27 on chain 26 will engage between the teeth of rack 38 and the boat will then be carried up along the cable 11, being supported thereon by the wheels 37^a, as shown in Fig. 4. As the boat moves up along the track, it will swing the arms 34, as indicated in Fig. 4, but, for any reason, should the boat become loose, it can move backwardly only a short distance when its rear end will contact the upper ends of the arms 34 and it will thus be held in stationary position. The arms 34 thus constitute guard members preventing the boat 125 sliding downwardly on the cables 11. The 130

boat is carried up onto and over the member 9 and is automatically released by chain 26 as the latter moves downward to sprocket 25. The boat then is free and coasts down 5 the track formed by the cables 10 by gravity. The boat stays on the track until it strikes the body of water B when it is projected outwardly along the surface of the water. The supporting sheaves 37^a then leave the 10 cables 10. Owing to the fact that the cables 10 can be pulled down by the tension cables 14 the boat strikes the water at a very small angle and any sudden or violent shock is eliminated. The boat receives sufficient 15 momentum from its travel downward on the cables 10 to move through the water and can be steered by the steering wheel 39^a back toward the aqueduct 16. The current moving in the said aqueduct will then again 20 carry the boat thereinto and it will be ready for another trip. By the arrangement of the track and aqueduct it will be seen that the boat makes a continuous circle and it is not necessary to reverse the direction of the 25 boat or of any of the mechanism. If desired, the boat can be rented to the pleasure seekers for a certain period and they can make repeated trips over the device without any help or attention from other parties. 30 If desired, heavy boats can be used which will plunge down into and sink into the water, or comparatively flat boats which will also become submerged. Such crafts would be used by bathers and can be propelled 35 back to the aqueduct 16 by the bathers.

From the above description it is seen that applicant has provided a simple and ingenious amusement or pleasure device and one which will afford great entertainment and 40 pleasure to a large number of people. By the use of the cables for the tracks a minimum amount of supporting structure is necessary and the device can be installed at comparatively small expense. The boat is 45 securely held on the track by deep grooved sheaves and their brackets and there is no dangerous feature in the invention.

It will, of course, be understood, that 50 various changes may be made in the form, details, arrangement and proportions of the parts without departing from the scope of applicant's invention, which, generally stated, consists in such a device as shown and described and defined in the appended 55 claims.

What is claimed is:

1. A pleasure device having in combination, an elevated support disposed adjacent a body of water, of a track extending up over said support and down into said water, an aqueduct leading from said body of water and aligned with the end of said track which is disposed away from said body of water, a steerable boat adapted 60 to run on said track and move in said

aqueduct, means for maintaining a current through said aqueduct, and means for lifting the boat on said track to said support and automatically releasing the same whereby the boat will coast down the track into 70 the water and may be steered back into the aqueduct so that a continuous round trip may be had.

2. A pleasure device adapted to be disposed adjacent a body of water having in combination, a pair of spaced supports, a track formed of spaced cables leading downward from said supports into said body of water, a track leading downward from said supports away from said body of water, 80 an aqueduct leading from said body of water and curved to align with said latter track and extending between said supports back to said body of water, means in said aqueduct for maintaining a current therein, a steerable boat having guiding and supporting means for engaging said tracks and movable through said aqueduct, means for propelling said boat upward along said latter track and releasing it for coasting movement down said first mentioned track whereby said boat can move continuously in a circuit down said first mentioned track into said body of water and be steered back to and carried through said aqueduct and up 95 said last mentioned track.

3. A pleasure device adapted to be disposed adjacent a body of water having in combination, a pair of spaced elevated supports, a convexly curved rigid member secured to the top of each support forming a track section, of a track cable secured to each end of said members and forming tracks adapted to support a boat extending downward therefrom and from said supports into said body of water and downward therefrom—and from said supports away from said body of water and a boat having means at each side adapted to rest on said tracks and move up the track extending away from said body of water and down the track extending toward said body of water.

4. A pleasure device adapted to be disposed adjacent a body of water having in combination, a pair of spaced elevated supports, a convexly curved rigid member secured to the top of each support forming a track section, of a track cable secured to each end of said members and forming tracks adapted to support a boat extending downward therefrom and from said supports into said body of water and downward therefrom and from said supports away from said body of water, a platform 115 secured to said supports beneath said curved track members, a motor carried on said platform, an endless chain driven from said motor and having its top run disposed substantially parallel to the track extending 120

125

130

4
downward away from said body of water, and a boat having means engaged by said chain adapted to move on said tracks.

5. A pleasure device adapted to be disposed adjacent a body of water having in combination, a pair of spaced elevated supports, a convexly curved rigid member secured to the top of each support forming a track section, of a track cable secured to 10 each end of said member and forming tracks adapted to support a boat extending downward therefrom and from said supports into said body of water and downward therefrom and from said supports 15 away from said body of water, an aqueduct extending from said body of water and curved to align with said track extending away from said body of water and between said supports back to said body 20 of water, a boat adapted to move in said aqueduct and on said track, means for propelling said boat on the track extending away from said body of water, and means carried by said supports for operating said 25 last mentioned means.

6. A pleasure device adapted to be disposed adjacent a body of water having in combination, spaced elevated supports, rigid convex track members secured to the 30 track of each support, a track extending downward from each end of said members, respectively, toward and away from said body of water, an endless chain adapted to move parallel to the track extending 35 away from said body of water and com-

prising spaced transverse pins, a boat movable on said track, a saw-toothed rack on the bottom of said boat adapted to be engaged by said pins whereby said boat will be propelled up said latter track and automatically freed to coast down the other track. 40

7. The structure set forth in claim 6, spaced inclined rigid frame members extending beneath said track extending away 45 from said body of water, guiding means for said chain on said frame members, and arms pivoted to said frame members adapted to be swung by the upward passage of said boat but preventing the downward 50 movement of said boat on said track.

8. A pleasure device adapted to be disposed adjacent a body of water having in combination, a pair of spaced elevated supports, a cable extending from each support downwardly into the water and forming a track, a cable extending downwardly from each of said supports away from said body of water forming a track, an aqueduct leading from said body of water to said latter track, and a boat having a pair of sheaves at each side adapted to contact with and be supported by said cables whereby said boat can be moved into said aqueduct of said last mentioned track and down said 55 first mentioned track into the body of water. 60

In testimony whereof I affix my signature.

HARRY AUPERL.
